(57) **CLAIM**

The ornamental design for a full distribution troffer luminaire, as shown and described.

DESCRIPTION

FIG. 1 is an enlarged bottom left perspective view of a full distribution troffer luminaire showing our new invention;

FIG. 2 is an enlarged bottom right perspective view of the luminaire illustrated in FIG. 1;

FIG. 3 is a top plan view of the luminaire illustrated in FIGS. 1 and 2;

FIG. 4 is a rear elevational view of the luminaire illustrated in FIGS. 1-3;

FIG. 5 is a left side elevational view of the luminaire illustrated in FIGS. 1-4;

FIG. 6 is a front elevational view of the luminaire illustrated in FIGS. 1-5;

FIG. 7 is a right side elevational view of the luminaire illustrated in FIGS. 1-6; and,

FIG. 8 is a bottom plan view of the luminaire illustrated in FIGS. 1-7.

The broken lines illustrate environmental structure and form no part of the claimed design.

The luminaire is shown broken away to indicate no specific length is claimed.

1 Claim, 4 Drawing Sheets
